Filed June 1, 1965, Ser. No. 85,542

Term of patent 14 years

(Cl. D64—11)

FIG. 1

FIG. 2

FIG. 3

FIG. 4

FIG. 1 is a front perspective view showing our new design of a casing for a check printing adder;

FIG. 2 is a rear elevational view thereof;

FIG. 3 is a top plan view thereof;

FIG. 4 is a right side elevational view thereof with parts of the broken line illustration of the carriage being cut away for convenience of illustration; and

FIG. 5 is a left side elevational view thereof.

The broken line illustrations of the keys and other elements are merely for illustrative purposes.

We claim:

The ornamental design for a casing for a check printing adder, as shown, and described.
